US00D740338S

(12) **United States Design Patent**
Ford

(10) **Patent No.:** **US D740,338 S**
(45) **Date of Patent:** **** Oct. 6, 2015**

(54) **LDC WELDER**

(71) Applicant: **Aaron J. Ford**, Provo, UT (US)

(72) Inventor: **Aaron J. Ford**, Provo, UT (US)

(73) Assignee: **Sunstone Engineering, Inc.**, Payson, UT (US)

(**) Term: **14 Years**

(21) Appl. No.: **29/493,135**

(22) Filed: **Jun. 5, 2014**

(51) LOC (10) Cl. **15-09**

(52) U.S. Cl.

USPC **D15/144**

(58) **Field of Classification Search**

USPC **D15/144, 144.1, 144.2**

See application file for complete search history.

(74) *Attorney, Agent, or Firm* — Wright Law Group, PLLC; Mark F. Wright

(57) **CLAIM**

The ornamental design for a LDC welder, as shown and described.

DESCRIPTION

FIG. 1 is a left-side perspective view of an LDC welder in an extended position showing the new design;

FIG. 2 is a right-side perspective view of an LDC welder in an extended position showing the new design;

FIG. 3 is a right-side view of an LDC welder in an extended position showing the new design;

FIG. 4 is a left-side view of an LDC welder in an extended position showing the new design;

FIG. 5 is a top view of an LDC welder in an extended position showing the new design;

FIG. 6 is a bottom view of an LDC welder in an extended position showing the new design;

FIG. 7 is a back view of an LDC welder in an extended position showing the new design;

FIG. 8 is a front view of an LDC welder in an extended position showing the new design;

FIG. 9 is a left-side perspective view of an LDC welder in a retracted position showing the new design;

FIG. 10 is a right-side perspective view of an LDC welder in a retracted position showing the new design;

FIG. 11 is a right-side view of an LDC welder in a refracted position showing the new design;

FIG. 12 is a left-side view of an LDC welder in a retracted position showing the new design;

FIG. 13 is a top view of an LDC welder in a retracted position showing the new design;

FIG. 14 is a bottom view of an LDC welder in a refracted position showing the new design;

FIG. 15 is a back view of an LDC welder in a retracted position showing the new design; and,

FIG. 16 is a front view of an LDC welder in a retracted position showing the new design.
